UNITED STATES PATENT OFFICE

2,379,710

GUN PORT MOUNTING

Arnold H. Heineman, Chicago, Ill., assignor to
The Guardite Corporation, a corporation of Illinois

Application September 18, 1943, Serial No. 502,909

7 Claims.

(Cl. 73—167)

This invention relates to a gun port mounting and more particularly to a means for mounting a gun, particularly a gun of high calibre, within a test chamber in such manner that the muzzle of the gun may be outside of the chamber while providing a seal which is air-tight and which will hold even during firing and recoil of the gun.

Owing to the diverse weather conditions which modern artillery may encounter, it has become desirable to test the operation of guns of all types within test chambers wherein the working parts may be subjected to extremes of temperature and pressure, ranging from the highest temperatures which may be encountered, to temperatures far below zero, to varying conditions of humidity, and to pressures as low as may be encountered in the highest airplane flight.

It is of course desirable to fire the guns under these conditions, and since the chambers are relatively small and the conditions therein would be upset by the firing of artillery within the chamber, even if no shell were employed, it is desirable that the muzzle of the gun be outside of the chamber. It is also desirable that the barrel of the gun be left free to move during recoil. The present invention provides a port within which guns having barrels of different sizes may readily be mounted without destroying the conditions within the chamber and leaving the gun free to recoil upon firing.

The invention is illustrated in the drawing in which Fig. 1 represents a sectional elevation of a portion of a test chamber through the gun port; Fig. 2 represents an enlarged sectional view of the port, corresponding to Fig. 1; and Fig. 3 is a sectional view along the line 3—3 in Fig. 2.

As shown in the drawing, the test chamber 10 contains a port 11 through which the barrel 12 of the gun 13 protrudes into the concussion chamber 50 which is joined to the test chamber by the expansion joint 51. The base 14 of the gun is firmly affixed to the base of the test chamber. Means are provided (not shown) for evacuating the chamber, for admitting air thereto, and for varying the humidity and temperature therein.

The gun port which is shown in greater detail in Fig. 2 comprises a retainer ring 15 which is welded to the wall of the port 11. On each side of the retainer ring is a flanged member 16 held in position by the bolts 17. The flange 18 on each of the members 16 is internally directed to hold in place the annular packing material

19. Within the retainer ring is a hollow recoil cylinder 20 having its inner surface 21 carefully machined and having on its outer side an annular boss 22 which extends into the chamber formed by the retainer ring 15 and the two flanged members 16.

Inside of the recoil cylinder is a stuffing box cylinder 25 which is provided on its outer surface with at least two ring grooves 26 within which are mounted piston rings 27, suitably lubricated. One side of the inner portion of the stuffing box chamber is cut away in the ordinary fashion to provide a packing chamber 28 of considerable depth. Within this chamber is mounted a gasket 29 having on each side thereof a fibre washer 30. The gasket and washers are packed in position by the gland 31 which may be operated by the gland screws 32.

The gasket 29 and the washers 30 are annular in form and their inner diameter is such as to bind tightly upon the gun barrel 12. The closure apparatus may be adapted for gun barrels of various sizes by substitution of gasket and washers of suitable size.

The stuffing cylinder may be held in place upon the gun barrel by the arrangement shown at the right of Figure 2. This comprises a clamping ring 40 which may be spaced from the stuffing cylinder 25 by any suitable means such as the adjusting bolts 41. The clamping ring 40 has an internal diameter greater than the internal diameter of the stuffing box chamber 28. The clamping ring may be secured to the gun barrel by the use of a series of wedges 42 which are driven between the ring and the gun barrel. It is understood that a series of wedges having various entering thicknesses may be employed for use on guns of various sizes.

The operation of the port will readily be understood from the foregoing description. The clamping ring-stuffing cylinder assembly is first slipped over the muzzle of the gun and located as far as suitable to the rear. The washer 30 followed by the gasket 29 and a second washer 30 are then placed in position followed by the gland 31 which may be tightened at any desired stage. It is preferred that the recoil cylinder be left permanently upon the stuffing cylinder due to the difficulty of inserting piston rings. This entire assembly may be placed upon the barrel at one time by removal of the outer flanged member 16 and the corresponding packing. The recoil cylinder may be secured in position by replacing the packing and the flanged member 16. The inner flanged member 16 and the corresponding pack-

ing are of course in position before insertion of the recoil cylinder. The wedges 42 are then driven into place to lock the entire assembly on the gun barrel, this not being done, however, until the gun has been secured in its position within the test chamber.

The annular boss 22 provides a limited universal connection between the gun and the port so that minor adjustments of position may readily be made without disturbing the seal.

Upon firing of the gun the entire stuffing box assembly may move with the barrel within the recoil cylinder upon the piston rings 27.

The seal may also be employed in high altitude airplane operations where a pressure differential exists between the outside and the inside of the plane. In such cases lock or other means should be provided in connection with the breech of the gun for loading. Such equipment is not necessary in the test chamber which may be reevacuated after each round.

The foregoing detailed description has been given for clearness of understanding only, and no unnecessary limitations should be understood therefrom.

What I claim as new, and desire to secure by Letters Patent, is:

1. A seal for a gun barrel comprising a stuffing box secured to the barrel, said box including packing, a gland, and a stuffing box cylinder, the outer surface of the cylinder being provided with at least two ring grooves; a piston ring in each ring groove; and a recoil cylinder enclosing the stuffing box and having an inner surface bearing on the piston rings, said recoil cylinder being adapted to be sealed in a wall provided with a port.
2. A seal as set forth in claim 1, in which the recoil cylinder is provided with an annular boss and said boss is movably sealed within a retaining ring.
3. A seal as set forth in claim 1, in which the stuffing box is provided with a clamping ring secured to the stuffing box, said ring having an internal diameter larger than the gun barrel and said clamping ring being secured to the gun barrel by a wedge.

4. A seal adapted for sealing gun barrels of variable outer dimensions within a port in a test chamber wall, comprising a stuffing cylinder having an internal diameter greater than the external diameter of the largest gun barrel to be sealed, a stuffing chamber within the stuffing cylinder adapted to contain packing, and a gland associated therewith and adapted to compress the packing upon a gun barrel and the stuffing cylinder, said stuffing cylinder being provided with at least two external ring grooves.

5. A seal adapted for sealing gun barrels of variable outer dimensions within a port in a test chamber wall, comprising a stuffing cylinder having an internal diameter greater than the external diameter of the largest gun barrel to be sealed, a stuffing chamber within the stuffing cylinder adapted to contain packing, a gland associated therewith and adapted to compress the packing upon a gun barrel and the stuffing cylinder, said stuffing cylinder being provided with at least two external ring grooves, piston rings in each of said ring grooves, and a recoil cylinder enclosing the stuffing box and having an inner surface bearing on the piston rings.

6. A seal as set forth in claim 5, in which the recoil cylinder is provided with a ring boss on its outer surface adapted to be sealed for limited universal movement in a test chamber port.

7. In combination with a hermetically sealed container including a wall having an aperture through which the barrel of a gun being tested is adapted to extend, a seal for said barrel, comprising a stuffing box secured to the barrel, said box including packing, a gland and a stuffing box cylinder, the outer surface of the cylinder being provided with at least two ring grooves; a piston ring in each groove; and a recoil cylinder enclosing the stuffing box and having an inner surface bearing on the piston rings and an outer surface in sealing engagement with the edges of said aperture.
